UNITED STATES PATENT OFFICE

1,961,053

POCKET CALCULATING MACHINE

Carl Kübler, Berlin, Germany

Application August 20, 1931, Serial No. 558,380
In Germany August 21, 1930

6 Claims. (Cl. 235—89)

The invention relates to a pocket calculating machine for addition and subtraction with numbered sliders. Devices of this kind for addition and subtraction are known, the slider being disposed therein between guides or on a guide grid, and enclosed in a box or casing of sheet metal, cardboard, celluloid or the like. The cover plates of the casing are provided with slots through which the sliders are actuated so as to bring the numerals into position opposite the display openings (through which the results can be read off).

Machines are known in which the adjustment both for the addition and the subtraction and also the display of the results take place on the same side, whereas, in other machines additions are made on the one side, and subtractions on the other, for which purpose the numbered sliders are correspondingly double sided. In these known machines the principle is nearly always the same, the only difference being the arrangement especially with regard to the transfer of the tens. For this reason there is no need to describe these machines in exhaustive detail.

Calculating machines with numbered sliders are also known in which the numerals for the addition are arranged on the front, and those for the subtraction on the back, the addition numerals being provided in serial order from 0 to 9 on the top half of the front, and the subtraction numerals—viewed from the addition side—in the same direction but upside down on the bottom half of the back.

In all these known calculating machines the total changes over continuously but irregularly from one side to the other, the machine showing a debit balance at one time and a credit balance at another. In no instance however, is it immediately possible to read the debit balance correctly and intermediate calculating is always necessary. However, the need has arisen for an adding and subtracting machine by means of which it is possible to calculate from the positive into the negative and vice versa without upsetting the numerals. Such machines are needed for accountancy control, especially double column reckoning, extracts from accounts-current and the like. In closing an account or ascertaining a difference it is not always possible with the existing devices to find out on which side above or below 0 the balance lies. The necessity for upsetting the figures i. e. deducting the smaller value from the higher—which is of frequent occurrence—is troublesome and disturbing and forms a source of error. This also applies to the aforesaid double-sided machine when the balance

is carried forward and changes from one side to another in an irregular manner. Although, in this known machine according to U. S. Patent 1,596,108 it is also possible to calculate with negative values, the negative value cannot be read off in the window opening. A red sign indicates, in this case also, the necessity for an intermediate calculation. However, the negative balance can be read off in the adjusting slots on the addition side, the value next the first (so called "white") opening being the desired value in all cases. To the result thus read off, being the complementary numeral to 9, there must always be added a unit in the last place on the right. To illustrate what is meant, an example is given with reference to the known "Addiator" calculating machine.

If, for example a credit sum of \$978.35 be set on the addition side of this machine, and the sum of \$1451.80 be subtracted therefrom, the openings on the addition side will display the figures 9526.55, and in the 7th place next the numeral 9 a red sign indicating that the result cannot be used in this form. On the subtraction side also the same result is displayed in the openings, and also with the red sign, indicating that the value requires an intermediate calculation before it can be used.

In the new machine the correct results 473.45 would appear and be readable at once. If the value set on the addition side is to be further reduced by a debit item 358.90, the openings in the known machine will read 9167.65 again with a sign in the 7th place, whereas according to the new system the value 832.35 is shown.

Typical embodiments of the present invention are illustrated in the drawings in which

Figure 1 is a diagrammatic illustration of the subtraction side of a two-sided "Addiator" calculating machine, with the two calculating panels disposed in accordance with the invention.

Fig. 1a shows the addition side of the same machine.

Figure 2 is a diagram of a double-sided slider for these calculating machines.

Fig. 2a shows a similar slider with the slots for receiving the point of the pencil or the like by means of which the slide is moved.

Figures 3, 3a and 4 represent the application of the invention to a one-sided addition and subtraction machine with two calculation panels and two rows of display openings, the slider being shown separately in Figure 4.

Figure 5 is a diagram of a slider for an addition and subtraction machine with a rotary cover

plate, such as shown, for example, in United States Patent 1,661,277, Thomas.

Figure 6 is a diagram of a slider for a one-sided addition and subtraction machine with rotary cover plate, but without a tens transfer sign.

Figure 7 is a view of a modified form of a slider intended for use in the right hand position.

According to the invention, the casing or box of the calculating machine is provided for the negative result of a calculation with a special row of openings in which the negative final result can be read off at once.

On the drawings, the casing *k* has, at one side, which may be denominated the subtraction side (Fig. 1), a plurality of first display openings *d*, operating slots 20, adjacent which are provided in the usual way the numbers 9 to 0 in descending order, and a lower row of special openings *c*. On the other side (which may be denominated the addition side, Fig. 1a) is provided a second row of display openings *d'*. Within the casing are movable a plurality of sliders, each of which has a plurality of columns of indicia thereon. It will be noted that the position of the casing is reversed 20 end for end between Figures 1 and 1a, so that a column of numbers on one slider, visible through an opening *d* on the subtraction side corresponds to a column of numbers on the same slider which are successively visible through the corresponding opening *d'*, so that the result appearing at the openings *d* is always identical with the result appearing at the openings *d'*.

On the other hand, the result appearing at the openings *c* is the complement of the result appearing at openings *d* and *d'*.

The addition and subtraction sliders *a* and *b*, are made—for example as shown in Figure 2—in one continuous piece. The two halves are then folded together along the connecting web. The 40 left half *a* (Figure 2) then comes into position on the back—the addition side—and the right half *b* on the front—the subtraction side. Whereas the slider *a* has remained unchanged, the subtraction slider, in addition to the inverted numerals 0-9—as viewed from the addition side—is provided with a second column of numerals 9-0, and between these two columns two other sections namely the usual signal section *f* and a further section bearing a minus sign. Consequently, the subtraction side is provided with eleven equal divisions between the top signal section, preceding 0, as far as the minus-sign section. On the subtraction side, the box *k* is arranged in the same manner as the known 50 Addiator machines, except that below the adjusting slots it is provided with a second row of openings *c* behind which the numerals of the lower column on the slider *b* are moved. These numerals are arranged in inverted order 9-0 60 (starting from the minus sign) on the slider *b* (Figures 1 and 2). Below the opening *c* of the first (Figures 1 and 2), the indication +1 is plainly placed on the right, the indication +1 is plainly marked, so that the reader must always add +1 at this place, that is to say, the indicated result 65 must always be increased by one unit. The row of openings *c* always displays the numerals complementary to 9 as compared with those displayed in the upper row *d*.

For example if the numeral 9 be present in the 70 first or upper opening *d* on the right in Figure 1, 0 will appear in the corresponding bottom opening *c*. If 1 be set in the third upper opening *d* from the right, the complementary value 8 on the same slide will appear in the row of openings 75 *c*. If 4 be set, the value 5 on the same slider will

appear in the lower opening *c*. If however, the signal be set in the top opening, a minus sign will appear in the lower opening *c*. In order to be able to effect this setting in the known calculating machines, it is important that the space available for free movement inside the box should be sufficiently large that at least one other position should be available for setting below 0, i. e. no blocking device is present to prevent this. It is also necessary that there should be subordinated to the signal in the top row of openings a second signal which must appear in the negative row of figures and must be fixedly related with the first one. This signal is then provided with the minus sign, so that both signals appear at the same time, the upper one indicating that the value in the top row of openings *d* is not to be read off (Figure 1), but that the true result is that having the negative sign, and is to be read off from openings *c* with the addition of one unit to the numeral visible at the right hand opening *c*. In the example shown in Figure 1, therefore the correct negative value to be read off, is not the 4109 visible in the top row of openings but 5890+1 in the row *c*.

Figures 3 and 4 represent the application of the invention to a machine in which the two calculation panels for addition and subtraction are provided on the same side. Here the upper row of openings *d* corresponds to that in Figure 1, 105 whilst the bottom row contains the openings *c* into which the lower values and the minus sign are moved. In this case also, the sliders are provided with the minus-sign section at the lower end. Ten equal sections are provided between 110 the two rows of openings or between the minus sign and the signal *f*.

Figure 7 represents a further simplification. From a comparison of the slider according to Figure 2 and the new slider for the first position 115 of a double-sided Addiator machine it will be evident that the addition members *a* have remained unaltered, whereas, in the first position on the right in the subtraction slider, no blank space is present at the end of the column, and the 120 minus section is replaced on this slider by the value 10. Thus this slider presents at openings *d* and *c* the pairs of indicia 0—10, 1—9, 2—8, etc., so that the numbers appearing at the two openings are supplemental to one another with respect 125 to 10.

The signal *f* has also been lowered by one space, and a new section (0) has been arranged between the signal *f* and the top numeral 9. On the other sliders the minus sign may be suitably replaced 130 by a red signal or the like above the bottom numeral 9, said replacement being indicated by 10 meaning that the value represented is 10 and is to be transferred as one unit into the next higher position.

In other respects the machine remains unaltered. Whereas, however, for the row of openings *c* in Figure 1, one unit must always be mentally added to the first position on the right in reading off the negative balance, this is dispensed 140 with in the new solution. Owing to this arrangement, the complementary value to 10 (instead of to 9) already appears in the first position of the row of openings *c*, so that the result can be read off at once as the final result.

This arrangement of the sliders enables calculations above 0 and below 0 to be directly calculated, or additions and subtractions may be alternated and the balance read off at once. A negative result is automatically displayed as 15

such and can be read off on the row of openings arranged for that purpose. With this arrangement the credits are always situated on the one side and the debits on the other, so there is no transfer from one calculation panel to the other, the result being to assure a high degree of simplification, clarity and ease in supervision. The person making the calculation recognizes the character of the balance at once, whilst the invention does not render the working of the machine more difficult or less easy to supervise. The arrangement is suitable for any currency and the machines do not require any other alteration than to be supplemented in accordance with the invention. For any other coinage—such as English—than the decimal system, the graduation of the sliders must be modified accordingly.

It is obvious that in order to operate the sliders it is necessary to engage them by means of a suitable instrument. For example, any sharp pointed instrument, such as a pin or needle, could be inserted in the operating slot and brought into engagement with the corresponding slider to move the same up or down, as desired. If desired, it would also be possible to provide a series of spaced apertures, dents, notches or the like in the sliders to receive the point of a pencil or other implement, as shown for example, in applicant's prior United States Patent 1,596,108. This, however, constitutes no essential feature of the invention and any suitable means may be provided for moving the sliders.

Normal additions and subtractions may be accomplished on this machine in the usual way. When, however, a "negative balance" comes into existence by subtracting a large sum from a small one, the effect is immediately indicated at the openings *d* (and *d'*) to show that the numerals visible at these openings do not represent any result which can be used directly. At the same time, a correct result is indicated at the openings *c*. Let it be assumed that the register (Fig. 1) has been brought to indicate \$978.35, as a result of successive additions and subtractions. Assume it now becomes necessary to subtract therefrom \$1451.80. It is obvious that a "negative balance" will occur. Before this debit of \$1451.80 is subtracted, the openings *d* show as a result of the operation of the machine the numerals 097835 (for the six right hand places); the openings *c* for the corresponding places show the numerals 902164 (+1). When this debit has been set up on the machine, the openings *d* (and *d'*) will show a signal, and a minus sign will appear at an opening *c*, so that the respective readings will be (at openings *d*) R52655, and (at *c*) —47344 (+1). The "R" designates the signal appearing at an opening *d* to indicate that no true result appears thereat. The minus sign at an opening *c* indicates that these openings give a true "negative balance". The "(+1)" indicates that a unit is to be added to the right hand digit as described above.

With the form of arrangement of the slider as shown in Figure 7, under the same conditions, the register openings *d* will indicate 097835 when the special openings *c* indicate 902165; and following the subtraction operation, the openings *d* will display R52655, and the openings *c* —47345.

70 I claim:

1. A pocket calculating machine for addition and subtraction, comprising a casing having a row of first display openings and a related row of special display openings therein, and sliders each having a first column of numbers from 9

to 0 and an oppositely directed column of numbers from 0 to 9, both said columns including the intermediate numbers in regular arrangement, said sliders being adjustably arranged in said casing to cooperate with said openings so that said first display openings each renders visible an individual number of said first column and simultaneously the corresponding special display opening renders visible the number on said oppositely directed column comprising a result complementary to the result visible at the corresponding first display opening, said sliders being so disposed in the casing that they may each be set to an additional signal position beyond the position at which the number 9 appears at the corresponding special display opening.

2. A pocket calculating machine for addition and subtraction, comprising a casing having a row of first display openings and a related row of special display openings therein, and sliders each having a first column of numbers from 9 to 0 and an oppositely directed column of numbers from 0 to 9, both said columns including the intermediate numbers in regular arrangement, said sliders being adjustably arranged in said casing to cooperate with said openings so that said first display openings each renders visible an individual number of said first column and simultaneously the corresponding special display opening renders visible the number on said oppositely directed column comprising a result complementary to the result visible at the corresponding first display opening, said sliders being so disposed in the casing that they may each be set to an additional signal position beyond the position at which the number 9 appears at the corresponding special display opening, at least one said slider having a minus sign at the additional signal position thereof.

3. A pocket calculating machine for addition and subtraction, comprising a casing having a row of first display openings and a related row of special display openings therein, and sliders each movable past a corresponding opening in each row, each slider having a plurality of columns of indicia thereon, one said column being visible at the corresponding first opening and including the numbers 0 to 9 arranged in succession and an additional signal section adjacent the 0, another said column of at least one slider including the numbers 9 to 0 arranged in inverted order for displaying at the corresponding special opening the number which forms the sum of 9 when added to the number of said one column displayed at said first opening, said other column also having a signal space with a minus sign adjacent the number 9 thereon and brought to display position at said special opening when the slide is moved from the display of 0 at the first opening to display the additional signal section thereof.

4. A pocket calculating machine for addition and subtraction, comprising a casing having a row of first display openings and a related row of special display openings therein, and sliders each movable past a corresponding opening in each row, each slider having a plurality of columns of indicia thereon, one said column being visible at the corresponding first opening and including the numbers 0 to 9 arranged in succession and an additional signal section adjacent the 0, another said column of at least one slider including the numbers 9 to 0 arranged in inverted order for displaying at the corresponding special opening the number which forms the sum of 9 when added to the number of said one column displayed at said

first opening, said other column also having a signal space with a minus sign adjacent the number 9 thereon and brought to display position at said special opening when the slide is moved from 5 the display of 0 at the first opening to display the additional signal section thereof, another said column of a further slider including the numbers 10 to 1 arranged in the opposite order for displaying at the corresponding special opening the 10 number complementary to 10 with respect to the number of said first column displayed at said first opening and also the number 0 adjacent the number 1 for display at the corresponding special opening when 0 is displayed at the corresponding first opening. 15

5. A pocket calculating machine for addition and subtraction, comprising a double-sided casing having first and second display openings on opposite sides thereof, and sliders each movable 20 in said casing for cooperation with a corresponding first opening and second opening, and each comprising an addition portion accessible for movement at one side and a subtraction portion accessible for movement at the other side, 25 each said addition portion having the numbers 9 to 0 thereon for display at said second openings, each said subtraction portion having thereon the numbers 0 to 9 arranged between two signals in ascending order and visible individually at said 30 first openings and having also a signal portion

including in columnar order a minus sign and the numbers 9 to 0 arranged in descending order, said addition and subtraction portions being connected so that the results visible at said first and second openings are identical, said casing also having a special row of display openings for rendering visible the figures of said signal portion complementary to the results visible at said first and second openings. 80

6. A pocket calculating machine for addition and subtraction, comprising a casing having first display openings therein, and sliders each carrying oppositely directed columns of numbers and adjustably arranged in said casing to cooperate with said first openings to display the numbers of one column thereat to indicate a result, said casing also having a row of special display openings for rendering visible the figures of the oppositely directed column complementary to the result visible at the first openings, the right hand slider having its oppositely directed column of complementary numerals displaced with respect to the numbers of said one column thereon to such extent that the number visible in the corresponding special display opening is always supplemental with respect to 10 and including also a number 10 arranged thereon in the column adjacent the 9 whereby to provide a supplement for the 0 in said one column. 85 90 95 100
